UNITED STATES PATENT OFFICE

JOSEPH SLADKY AND ALEXANDER C. SLADKY, OF MILWAUKEE, WISCONSIN, ASSIGNEES TO NATIONAL ENAMELING & STAMPING COMPANY, INC., OF MILWAUKEE, WISCONSIN

FUEL MIXER

Application filed February 18, 1929. Serial No. 340,992.

This invention relates to new and useful improvements in fuel mixers.

One of the objects of our invention is the provision of a fuel mixing device adapted to be used in connection with liquid fuel burners and to be positioned within the liquid fuel supply tank whereby to provide for a mixture of fuel and air as the fuel is drawn from the tank to the burner.

10 Another and very important object of our invention is the provision of a mixing device which will create a mixture of air and gasoline or other liquid fuel at a constant rate so that the mixture will burn with a steady flame 15 at all times.

A further object of our invention is the provision of a liquid fuel mixer which employs the principle of the venturi wherein the air pressure utilized will at the throat of 20 the venturi increase in velocity and decrease in pressure so that when the air comes into contact with the liquid fuel it will readily mix therewith and the increased velocity will have a tendency to create a steady and 25 constant flow of the liquid fuel to create an even mixture and a steady flow of the fuel to the burner.

A still further object of our invention is the provision of a fuel mixture which is so 30 constructed and arranged that it may be readily used in connection with liquid fuel supply tanks of various types and can be quickly and easily connected to liquid fuel burners of various types.

35 With the above and other objects in view, the invention consists in the novel features of construction, the combination and arrangement of parts hereinafter more fully set forth, pointed out in the claim and shown 40 in the accompanying drawing wherein:

We have illustrated our improved liquid fuel mixer in position within a liquid fuel supply tank 1, the tank 1 is provided with the usual opening having an internally threaded 45 collar 2 fitted within the opening and retained in position by the annular flange 3.

Threaded into the collar 2 is a fitting 4 which is used for connecting the mixing device with the burner through the medium of 50 the conduit 5. The inner end of the fitting is

provided with a reduced tubular portion 6 upon which is mounted the upper end of the tube 7. This tube 7 forms the main housing for the mixing device and is used as the main air chamber for receiving the air under 55 pressure within the tank 1 to be utilized in mixing with the fuel from the tank.

The fitting 4 is provided at its inner end with an enlarged bore 8 which communicates with the central bore 9 of the fitting, and arranged within this bore 8 is the mixing tube 10. This tube 10 is somewhat smaller in diameter than the tube 7 so as to provide the air chamber 11 and the inner end of the tube 7 is formed with a reduced collar 12 embracing 65 the tube 10 adjacent its lower end to close the lower end of the air chamber 11.

Arranged within the tube 10 at its lower end is the fuel feeding tube 13, the lower end of which extends downwardly below the 70 lower end of the tube 10 toward the bottom of the tank 1. This tube is held in position by means of the reduced collar 14 on the lower end of the tube 10 and embracing the tube 13. This structure not only retains the 75 tube 13 in position but closes the lower end of the tube 10.

At the intermediate portion of the tube 10, a venturi 15 is formed with the inner end of the tube 13 terminating at the throat of the 80 venturi which leaves a very small space between the end of the tube 13 and the walls of the tube 10. The tank 1 contains not only the liquid fuel but air under pressure above the fuel and as this air under pressure is usually 85 at the top of the tank, the tube 7 is provided with inlet openings 16, admitting air to the chamber 11. This air passes downwardly into the chamber and through openings 17 90 in the tube 10 near the inner end thereof, the air passing into the mixing tube 10 and upwardly through the venturi 15. It will be noted that the air when passed through the Venturi throat at a certain velocity, the 95 velocity is increased and the pressure decreased at that point as compared with the pressure in the body of the tube and in the tank. This action will cause a steady and constant flow of the fuel through the tube 13 and create a 100

steady mixture as the fuel is delivered to the burner.

With the use of this improved mixing device, it will be apparent that when the control valve to the burner is opened and fuel drawn from the tank 1, the action of the Venturi throat will result in a lean mixture being delivered to the burner when the fuel is ignited. This lean mixture delivered to the burner at the beginning of the delivery of fuel to the burner, is due to the fact that when the burner valve is first opened there is more air sucked out through the mixing tube 10, than gasoline, but as the suction continues and the fuel is drawn up through the tube 13, the mixture will increase in its richness in gasoline, thus as the burning continues, the gasoline richness increases, providing a hot steady flame with very little loss of air from the tank 1.

Due to the arrangement of the venturi 15, the air when passing through the venturi will have its velocity increased and the pressure decreased as compared with the pressure in the remainder of the tube and in the tank.

It will be apparent from the foregoing that we have provided an extremely simple liquid fuel mixing device which can be quickly and easily attached to the fuel supply tanks of liquid fuel burners and wherein the device provides a mixture of air and liquid fuel at a constant rate so that the mixture will burn with a steady flame at all times.

We claim:

35 In a fuel mixer, a fitting having longitudinal bores, an externally threaded portion at one end of the fitting and an enlarged bore within the threaded part, a tubular portion at the outer end of the threaded part forming 40 a continuation of the bore, a tubular member having one end fitted over the tubular portion, a second tubular member within the first member having its one end extending into the enlarged bore, a reduced collar on 45 the first tube adapted to embrace the second tube adjacent its outer end, a venturi within the second tube intermediate its ends, a fuel feeding tube leading into the second tube with its inner end positioned at the venturi 50 and a reduced collar on the second tube embracing the fuel feeding tube adjacent its outer end.

In testimony that we claim the foregoing we have hereunto set our hands at Milwaukee, in the county of Milwaukee and State of Wisconsin.

JOSEPH SLADKY.
